UNITED STATES PATENT OFFICE.

ROY M. LYON, OF DENVER, COLORADO, ASSIGNOR OF THREE-TENTHS TO GUY C. WALTER, OF DENVER, COLORADO.

SHOCK-ABSORBER.

1,089,002.

Specification of Letters Patent. Patented Mar. 3, 1914.

Application filed March 24, 1913. Serial No. 756,336.

To all whom it may concern:

Be it known that I, ROY M. LYON, citizen of the United States, residing in the city and county of Denver and State of Colorado, have invented certain new and useful Improvements in Shock-Absorbers; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

15 My invention relates to improvements in shock absorbers more especially adapted for use in connection with automobiles and motorcycles or similar machines, though my improvements may be employed in other 20 relations where substantially the same function is required.

The device consists of a vertically tubular structure having liquid containing chambers at its opposite extremities in which 25 travel pistons connected with the opposite ends of a rod, the latter being centrally connected with an arm secured to the body of the vehicle so that as the body vibrates or moves up and down, the pistons will be reciprocated in their respective chambers. 30 Each chamber is composed of inner and outer shells both of which are cylindrical and stationary. The inner shell of each is provided with a number of triangular slots, 35 the said slots being widest at the top in the lower chamber and widest at the bottom in the upper chamber. As the pistons reciprocate, that in the lower chamber moving downwardly and traveling toward the points 40 of the slots, the area of the outlet for the liquid from the compartment below the piston through these triangular ports, is continually diminishing thus offering increased 45 resistance to the travel of the piston as it moves downwardly in the lower chamber. Each piston is equipped with a vertically 50 movable valve disk for controlling perforations in its body portion. The valve disk, of the lower piston is on the lower side of the 55 piston and closes the perforations in the piston as the latter moves downwardly, thus preventing the escape of liquid through the piston during its downward movement. The valve disk of the upper piston is reversely 60 arranged being mounted above the body of

the piston and consequently opens during the downward movement thus allowing the liquid to flow freely through the upper piston from the compartment of the chamber below the piston to the compartment above 60 when the piston is traveling downwardly. However, when the pistons are moving in the opposite direction the valve of the lower piston opens and the liquid passes freely from the upper compartment of the chamber into the lower compartment while in the case of the upper piston the valve closes during its upward movement and the escape of liquid from the upper compartment to the lower compartment takes place by virtue of 70 the triangular slots in the inner shell of the chamber. And as these slots diminish in area toward the top of the chamber, the resistance offered by the liquid in the upper compartment to the upward travel of the 75 piston, increases gradually during such upward travel. Each chamber is provided with a stuffing box through which the piston stem or rod passes, these stuffing boxes forming liquid tight joints.

Having briefly outlined my improved construction I will proceed to describe the same in detail reference being made to the accompanying drawing in which is illustrated an embodiment thereof.

In this drawing, Figure 1, is an end view of the running gear of an automobile showing two of my shock absorbers in place. Fig. 2, is a section taken on the line 2—2 Fig. 1, looking toward the left, the parts 85 however being shown on a much larger scale. Fig. 3, is a section taken on the line 3—3 Fig. 2, looking downwardly or in the direction of arrow 3. Fig. 4, is a detail view of the piston looking in the direction of arrow 90 4 Fig. 2. Fig. 5, is a detail view of the inner shell of the lowermost piston chamber.

The same reference characters indicate the same parts in all the views.

Let the numeral 5 designate a cylindrical tube into the opposite extremities of which are threaded stuffing boxes 6, the outer extremities of these boxes being shouldered and, interiorly threaded as shown at 7 to receive the threaded extremities of the outer shell members 8 of the piston chambers. Each shock absorber unit is connected with the vehicle by passing the lower stuffing box through an opening 9 formed in a plate 10 which is secured to the axle 12 of the ve-

hicle by means of U-shaped bolts 13. A lock nut 14 is interposed between the upper surface of the plate 10 and the lower extremity of the tube body 5. It is preferred to allow 5 the tubular body 5 a limited degree of movement and to this end the lock nut 14 may not be screwed tightly against the plate 10.

Within each outer shell 8 of each chamber is located a cylindrical shell 15 in which is 10 formed a number of triangular slots 16, these slots diminishing in area from the top toward the bottom in the lower chamber and from the bottom toward the top in the upper chamber. The inner shell members 15 fit closely within the outer shell members of the respective chambers and are held securely in place by means of screwed caps 17 which are applied to the upper and lower extremities respectively of the shells 8 of 15 the two chambers. The stuffing boxes close the chambers at one extremity of each, being the upper extremity of the lower chamber and the lower extremity of the upper chamber. Within each of these chambers is 20 located a piston 18, the two pistons being connected as shown at 19 with the opposite extremities of a rod 20 which is centrally reinforced as shown at 21 and provided with an opening 22 to receive the extremity 23 of 25 an arm 24 secured to the body 25 of the vehicle as shown at 26. The extremity 23 is partially ball shaped to permit a limited degree of movement between the tubular body of the shock absorber and the arm to provide 30 for different vibratory conditions incident to the use of vehicles of the character with which my improvement will be employed. This construction co-operates with the relatively loose connection between the 35 shock absorber and the plate 10 heretofore described. To the free extremity of the arm 24 is applied a stop washer or plate 27 which is slightly curved to permit a limited degree of movement between the shock absorber 40 structure and the body of the vehicle, the structure of this washer corresponding to and co-operating with the ball construction 45 of the arm extremity heretofore explained.

The body of each piston 18 is provided 50 with ports or perforations 28 adapted to be closed by a valve disk 29 when the lower piston is moving downwardly and when the upper piston is moving upwardly. For this reason the valve disk of the lower piston is 55 located below the body of the piston while the corresponding disk of the upper piston is located above the piston body, of the piston by means of screws 30 which are made fast to the valve disk and are freely slidable 60 within the piston body, the shanks of the screws being of sufficient length to permit the necessary opening and closing movement of the valve disk, spiral springs 31 being interposed between the screw heads and the 65 piston body. These springs are compara-

tively weak and yield readily to the pressure of the liquid when it passes through the ports 28 of the piston body, during the downward movement of the upper piston and during the upward movement of the 70 lower piston.

The outer shell of the lower chamber is provided with a port 32 to permit the filling of the chamber with liquid, preferably oil. This port is normally closed by a screw 75 plug 33. The cap 17 of the upper chamber is provided with a similar port 34 normally closed by screw plug 35 the port 34 being also utilized for filling the chamber with liquid.

In order to regulate or vary the passage 80 of the liquid from one compartment of either chamber to the other during the downward travel of the lower piston and during the upward travel of the upper piston, a valve 85 plate 36 of triangular shape to conform to the shape of one of the slots 16 of each inner shell but of less area may be employed. Each of these valve plates may be mounted upon a screw 37 which is threaded in an 90 opening 38 formed in a lug 39 of the valve plate the said lug extending into a narrow cavity 40 extending beyond the body of the outer shell 8 of each chamber. The screw 37 is journaled in the offset portions 41 and 95 42 of the shell at the top and bottom respectively of the cavity 40. One extremity of each of these screws is shaped as shown at 100 43 to receive a port key or wrench whereby the screw may be operated for the purpose 105 of adjusting the position of the valve plate within its slot 16. If it is desired to increase the resistance to the downward travel of the lower piston and the upward travel of the upper piston, these valve plates may 110 be moved toward the smaller extremities of the slots in which they are located and when the edges of the valve plates are brought into engagement with the adjacent edges of the inner shell members the passage of liquid through the slot will be cut off after the piston has entered the chamber zone in which the valve plate is located.

A result in a general way similar to that obtained by my improved shock absorber 115 could be obtained by the use of a single cylinder and a single piston therein, with its stem extending through at least one of the end caps of the cylinder for attachment to a bracket similar to the bracket 24 of 120 this application. This construction, however, would not be practical for use upon automobiles or for other purposes where the shock to be withstood runs up as high as one or two thousand pounds or possibly 125 higher. If the stem were extended through a cylinder and cap it would be necessary to pack the opening through which the stem passed extremely tightly in order that it might withstand the force of heavy blows 130

and if such a hard packing were employed there would be no give where merely slight obstacles were encountered and the device would thus prevent the springs of the vehicle from acting. In the construction of my invention there is no necessity for very tight packing of the piston stems and consequently they may slide comparatively freely thus not detracting to any appreciable extent from the resilience of the springs when the vehicle is passing over the slight obstacles to be encountered upon city streets and good roads.

From the foregoing description the use and operation of my improved shock absorber will be readily understood.

By reference to Fig. 1, the manner of applying my shock absorbers to the rear axle 12 of an automobile will be understood. As 20 the arms 24 connected with the body 25 of the vehicle as heretofore explained move downwardly, the pistons 18 in the lower chambers in the shock absorbers will travel in a corresponding direction and force the 25 liquid from the compartments of the chambers below the pistons through the slots 16 and into the compartments of these chambers above the pistons. At the same time the liquid in the upper chambers will move 30 freely from the lower compartments to the upper compartments as the valve disks 29 of the upper pistons will open freely against their springs 31 in response to the pressure 35 of the liquid as it passes through the piston openings 28. Again as the vehicle body moves upwardly the reverse movement is imparted to the pistons in the two chambers, the liquid in the upper chambers resisting the upward travel of the corresponding 40 pistons while the liquid in the lower chambers travels freely through the openings 28 of the pistons as the valve disks of the lower pistons open in response to the pressure of the liquid as it passes downwardly 45 through the piston openings 28.

While I have illustrated in the drawing and described in the specification the openings or cavities in the inner surfaces of the piston chambers as triangular in shape, the 50 said openings or cavities diminishing in width from the top toward the bottom in the lower chamber and from the bottom toward the top in the upper chamber, it must be understood that the invention is not limited to this particular shape of opening, as these openings may be of different shape or contour and as long as they vary in cross-sectional area between the upper and lower extremities of the chambers they will still 55 be within the scope of my invention as outlined by the appended claims.

Having thus described my invention, what I claim is:

1. A shock absorber, comprising upper 60 and lower chambers having shallow cavities,

lengthwise disposed in the inner surfaces of their walls, the said cavities diminishing in area from the top toward the bottom in the lower chamber and from the bottom toward the top of the upper chamber, pistons 70 mounted in the said chambers, and a stem connecting said pistons, each piston having valve controlled orifices, the valves being arranged to close the said orifices during the downward movement of the lower piston and during the upward movement of the upper piston, the said orifices, during the reverse movements of the said pistons being open to permit the passage of fluid, substantially as described.

2. A shock absorber, comprising a vertically disposed tubular body member, chambers connected with the body member at the opposite extremities thereof, each chamber being composed of inner and outer 85 shells, the inner shell of each chamber being provided with slots which diminish in area from the top of the chamber downwardly in the lower chamber and from the bottom of the chamber upwardly in the upper chamber, pistons located in the respective chambers, a stem connecting the said pistons, each piston having perforations and being equipped with a movable valve disk normally closing the perforations 90 therein, the valve disk of the lower piston being arranged to open during the upward movement of the said piston, while the valve disk of the upper piston is arranged to open during the downward movement thereof.

3. A shock absorber, comprising a vertically disposed body member, chambers connected with the opposite extremities of the said member, each chamber being composed of separable inner and outer shells closely 105 fitted together and connected to form a substantially integral device, the inner shell of each chamber having slots extending lengthwise of the shell, the slots of the shell of the lower chamber diminishing in width 110 from the top toward the bottom, while the width of the slots in the inner shell of the upper chamber diminish in width from the bottom toward the top, pistons fitted within the inner shells of the respective chambers, a stem connecting the said pistons, the pistons having ports and equipped with valves 115 arranged to close the said ports during the downward movement of the lower piston and during the upward movement of the 120 upper piston.

4. A shock absorber, comprising a body member adapted to be connected with the axle of a vehicle, chambers connected with the opposite extremities of the said member, each chamber being composed of inner and outer shells fitted together to form a substantially integral device, each chamber being closed at the top and bottom, the inner shells of the respective chambers hav- 125 130

ing elongated openings formed therein and extending lengthwise thereof, the said openings diminishing in area from the top toward the bottom in the lower chamber and 5 from the bottom toward the top in the upper chamber, pistons located in the said chambers and fitted into the inner shells thereof, the pistons having check valves, the said valve of the lower piston being 10 arranged to close during the downward movement of the piston, and to open to permit the free passage of liquid during the upward movement of the piston, while the check valve of the upper piston is reversely 15 arranged, and a stem connecting the two pistons and adapted to be connected with the vibrating body of a vehicle, substantially as described.

5. A shock absorber, having upper and 20 lower chambers, having shallow cavities formed in the inner surfaces of their walls, the said cavities extending lengthwise of the chambers and varying in cross-sectional area between the top and bottom of the 25 chambers; pistons mounted in the said chambers and a stem connecting said pistons, each piston having a valve-controlled opening, the valves being arranged to close said openings during the downward movement 30 of the lower piston and during the upward

movement of the upper piston, the said orifices during the reverse movement of the said pistons being open to permit the passage of fluid, substantially as described.

6. A shock absorber, comprising a vertically disposed body member, chambers connected with the body member at the opposite extremities thereof, each chamber being composed of inner and outer shells fitted closely together, the inner shell of each 40 chamber being provided with openings extending vertically of the chamber and varying in cross-sectional area between the upper and lower extremities of the said openings; pistons located in the respective chambers, 45 a stem connecting the said pistons, each piston having a valve-controlled opening, the valve of the lower piston being arranged to open during the upward movement of the said piston, while the valve of the upper 50 piston is arranged to open during the downward movement thereof for the purpose set forth.

In testimony whereof I affix my signature in presence of two witnesses.
